MATERIAL DISPOSAL APPARATUS

Seth M. Gooder, Deerfield, Ill.

Application October 28, 1941, Serial No. 416,920

10 Claims. (Cl. 61—83)

The present invention has for its object to provide means for efficiently and quickly emptying dumping cars and disposing of their contents.

When excavating tunnels, subways, or the like, the excavated material is usually hauled away in small dump cars which must be unloaded and the contents be then raised to the surface of the ground for final disposal. So, also, in other places, it may be advantageous to carry material in a train of cars to an unloading point. Viewed in one of its aspects, the present invention has for its object to make it possible to empty dump cars, one at a time, without uncoupling them from the train, as they reach the unloading point or station.

In carrying out my invention, I employ a rotatable cage at the dumping station, couple together a train of cars in such a manner that each car may turn with the cage, when positioned in the same, without uncoupling it from adjacent cars. In this way each car is simply turned over to dump its load, upon reaching the unloading station, and is then restored to its upright position so as to permit the train to move ahead a car length and bring the next car into dumping position. In this aspect of the invention, the apparatus is useful wherever large quantities of material must be moved, regardless of what happens to the same after being dumped.

A further object of the present invention is to provide a simple and novel arrangement for associating with a car dumping apparatus an air-lock which permits the material to be transferred from a tunnel to the outside, or in the opposite direction, without permitting the escape of any objectionable amount of air when the air in the tunnel or subway is being maintained under a considerable pressure.

A further object of the present invention is to provide an automatic interlock between a hoist located in a shaft close to a tunnel, subway, or the like, and the transferring apparatus for excavating material, whereby no material can be delivered into the shaft unless the hoist for the apparatus is ready to receive it.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a vertical section through the ground at and below the bottom of a tunnel, or

the like, at an unloading or dumping station, showing in elevation a train of cars and the dumping apparatus or mechanism and the air-lock; Fig. 2 is an elevation, on a much larger scale, of a fragment of the rotatable drum in the air-lock; Fig. 3 is a section on line 3—3 of Fig. 2, Fig. 4 is a section taken approximately on line 4—4 of Fig. 1; Fig. 5 is a diagram illustrating the electric control system; Fig. 6 is a section, on a larger scale than Fig. 1, on line 6—6 of Fig. 1; Fig. 7 is a section on line 7—7 of Fig. 6; Fig. 8 is a section taken approximately on line 8—8 of Fig. 7, but on a smaller scale, and showing only the air-lock portion of the apparatus; Fig. 9 is a section taken approximately on line 9—9 of Fig. 7, on the same scale and showing the same apparatus as Fig. 8; Fig. 10 is a longitudinal central section through the driven end of the air-lock drum and adjacent mechanism, namely 10 the end at the righthand side in Fig. 7; Fig. 11 is a face view of one of the ratchets appearing in Fig. 10, together with the pawl cooperating with the same; Fig. 12 is a view partly in longitudinal section and partly in elevation, illustrating one of the couplings between cars; Fig. 13 is a section on line 13—13 of Fig. 12; and Fig. 14 is a horizontal section through one of the socket members, with the corresponding end of the coupling bar shown in elevation in working position in the socket.

In the drawings the present invention has been illustrated as embodied in an apparatus or mechanism for handling material excavated in the digging or boring of a tunnel, or the like, including the hoisting of the material to the surface of the ground; and, for the sake of brevity, the detailed description will be confined to this particular form of the invention, since the utility of the whole or parts thereof, in other fields, will 35 be self-evident.

Referring to Figs. 1 and 4 of the drawings, 1 represents the floor of a tunnel on which have been laid rails 2 for supporting dump cars 3. Below the bottom of the tunnel, at a point which 40 is to serve as an unloading station, there is a pit 5 from the bottom of which a passage 6, preferably rectangular in cross section, of large area, extends laterally and downwardly until it meets a vertical shaft 7. This shaft may extend to the surface of the ground and be carried up still higher, in the form of a tower, as in my prior Patent No. 2,190,004. In the pit is an air-lock, material transferring unit A, driven by a suitable motor B, which may be similar to that illustrated 45 in my prior Patent No. 2,227,749. Above the pit

is a rotary cage 8 adapted to receive a dump car, the contents of which may be dumped into the transferring unit when the dump car is turned upside down.

As best shown in Figs. 6 and 7, the air-lock transfer device comprises a stationary cylindrical shell 9 closed at the ends, the axis of the cylinder being horizontal and extending lengthwise of the tunnel. The shell contains large openings 10, 10 in the top and bottom, the length of the openings being almost as great as the length of the shell. The lowermost opening registers with the upper end of the inclined passage or chute 6. Within the shell 9 is a rotatable cylindrical drum 11 having in the cylindrical wall thereof an opening 12 about the same length and width as one of the openings 10. The drum is somewhat smaller in diameter than the shell 9 and carries on its periphery a series of sealing units. In the arrangements shown, each sealing unit comprises two metal strips 14 and 15 and an intervening strip 16 of packing material, preferably soft rubber. These strips extend the entire length of the drum parallel with the axis of the drum. The strip 14 is fastened directly to the outer surface of the drum, while the strips 15 and 16 are secured to one side of the strip 14 by suitable screws 17. Upon tightening the screws 17, the rubber strip is compressed and expanded somewhat in the radial direction to insure good contact between the same and the surrounding shell. These sealing units are distributed approximately uniformly about the periphery of the drum, except that two of them lie directly on opposite sides of the opening or window. As in the later of my aforesaid patents, the effective capacity of the drum is that of a receptacle 18 fixed within the drum with its open side constituting the effective opening into the drum.

The shell or casing 9 and the ends of the drum proper, 11, are closed by sturdy disks 19 secured to the ends of the shell by screws 20. The drum has at each end a narrow peripheral flange 21 that fits within the surrounding shell and, surrounding the drum, adjacent to each flange, are a packing ring 22, preferably of rubber, and a clamping ring 24, which are conveniently fastened to the corresponding flanges by screws 25. By tightening the screws 25, the rings 24 are drawn toward the corresponding flanges 21, thereby compressing the packing rings and expanding them radially into engagement with the surrounding shell or casing. This packing at the ends of the drum, together with the longitudinal packing units, effectively seals the unit against the passage of air through the same, except such air as may be contained in the material which is delivered into the drum for the purpose of discharging it into the inclined passage or chute 6.

The cage 8 has wide, ring-like end sections 26 which rest on flanged rollers 27 mounted upon the shell or casing 9 in a manner to form a cradle for the cage. In the arrangement shown, there are two upwardly-diverging plates 28 rising from opposite sides of the upper opening 10 in the stationary shell; these plates being of the same length as said opening. Spanning the space between the ends of the plates 28 and extending well beyond the same are two stationary vertical plates 29 fixed to and rising from the top of the shell 9. The upper edges of the plates 29 are curved to fit the rim-like end sections 26 of the cage. The supporting wheels for the cage are conveniently mounted on laterally-projecting

flanges 30 at the ends of the plates 28; these flanges in turn being braced by means of sturdy brackets 31 fixed to the periphery of the shell 9 and having portions lying against and extending along these flanges.

Within the cage is a flat bed, which may consist simply of a pair of sturdy cross ties 32, provided with rails 34 that register with the rails 2 in the tunnel proper when the bed is in a horizontal position at the bottom of the cage. Within the cage, above and on opposite sides of the rails 34, are a pair of stiff angular plates 35 extending throughout the length of and rigidly fixed to the cage. These angular plates are of such a size and shape and are so disposed that then the usual dump car, comprising a little wheeled chassis 36 and a hopper-like body 37 is run into the cage, the noses or corners of the angular plates extend in close to the body and overlie the chassis, while the upper portions of the plates lie fairly close to and approximately parallel with the sides of the car body. When the cage is rotated, these heavy angle plates support the car except at times when it is resting on the rails. Each car is provided with couplings C so disposed that their longitudinal axes register with the longitudinal axis of the cage 6. By properly constructing these couplings, as will hereinafter be explained, any car in a train of cars may be entered in the cage and be rotated with the latter without being disconnected from the cars before and behind it, thereby making it unnecessary to uncouple the cars in order to be able to overturn them, one at a time.

It will be seen that the stationary plates 28 and 29 form a hopper into which the contents of the car are dumped when the car is overturned; this hopper directing the charge into the receptacle within the drum when the mouth of the latter is up, as shown in Fig. 6.

So far as the handling of the material entering the drum is concerned, this is the same as in the apparatus of my aforesaid Patent No. 2,227,749. In other words, when the drum is turned through an angle of one hundred eighty degrees from the position indicated in Fig. 6, the mouth or entrance to the same registers with the lower opening 10 in the stationary shell or casing 9 and with the upper end of the inclined discharge passage or chute 6. After the drum has dumped its charge, a further turning movement of one hundred eighty degrees brings it back into the receiving position, where it is ready to receive another load.

From the chute 6, the material flows into the bucket 37 of a suitable hoist, when the latter is down.

I have provided a suitable drive means and a controlling system therefor to permit the cage to be turned through a single revolution, so as to dump the load of a car therein and then return the car to its upright position; and then to cause the drum to rotate and deposit the load or charge into the discharge chute and again return to its receiving position; and to prevent the operation of the drum except when the bucket in the hoist apparatus is in position to receive material flowing down through the discharge chute.

Both the drum and the cage are driven by the motor B; the motor being of the reversible type so that when it turns in one direction it operates the cage, while the drum is turned when the motor is reversed. In the arrangement shown, the drum is provided with long trunnions

or shaft sections 38 and 39 extending out through the end walls 19. The trunnion or shaft section 38 is provided with a counter-weight 40 that serves to balance the drum. Surrounding and loose upon the shaft section 39 is a large gear wheel 41 which meshes with another large gear wheel 42 fixed to one end of the cage. On the shaft section 39, outwardly from the gear wheel 41, are two ratchet wheels 44 and 45; the ratchet wheel 44 being loose on the shaft and the other being keyed to the shaft, as indicated at 46 in Fig. 10. The ratchet wheel, 44, as best shown in Fig. 10, is secured to the large gear wheel 41 by screws 47. Also loose on the shaft section 39 is a pan-shaped housing 48 that has a heavy hub 49 which serves as one element of a coupling D between the member 48 and the shaft of the motor. Mounted within the housing 48 are two spring-pressed pawls 50 and 51 cooperating with the ratchets 44 and 45, respectively. Consequently, when the motor is turned in one direction, namely the clockwise direction in Fig. 8, the pawl 50 drives the ratchet wheel 44 and the large gear wheel 41, so that turning of the cage results. Upon reversing the motor, the pawl 51, which previously rode idly over the ratchet wheel 45, drives the latter ratchet wheel and, therefore, the material transferring drum and air lock.

I have provided a control system for the motor so that, upon starting the latter, it turns the cage through a complete revolution and then stops; thus causing a filled car within the cage to be turned over so as to dump its contents, and then to be returned to an upright position. Then, upon reversing the motor, the drum, into which the load has just been dumped, is turned through a complete revolution; thus allowing the contents to be spilled from the drum into the chute 6 and into the bucket 37 of the hoisting apparatus, after which the drum is restored to the material-receiving position and the motor stops. This control system is illustrated diagrammatically in Fig. 5. Referring to the diagram, 52 represents the handle and movable member of a double-throw switch having two stationary contacts 54 and 55, with either of which the movable switch element may be engaged. Normally, the movable switch member stands in an idle position, clear of both of the contact pieces. 56 and 57 are the lines for supplying current for energizing the motor. One of these lines is connected directly to a terminal on the motor while the other is connected to a terminal 59 on the main switch, which terminal is connected to the movable switch member. The stationary contact piece 54 of the main switch is connected to a contact finger 60 by means of a wire 61. This contact finger rides on the periphery of a ring 62 of conducting material which, as will be hereinafter explained, is fastened to and rotates with the large gear wheel 41. A second contact finger 64 engages the ring 62 and is connected by a wire 65 to a second terminal on the motor. When the movable member of the main switch is swung toward the right in Fig. 5 and engaged with the stationary contact 54, the motor becomes energized; the motor being caused to rotate in what may be termed the forward direction, namely the direction required to turn over the cage. The stationary contact 55 of the switch is connected to a contact finger 66 by a wire 66a. This contact finger bears on a ring 67 of conducting material which, as will hereinafter appear, is

fixed to the drum so as to rotate therewith. Another contact finger 68 engages with the ring 67 and is connected to a third terminal on the motor through a wire 69. Consequently, when the switch handle is swung toward the left in Fig. 5, so as to close the circuit at the stationary contact 55, the motor is energized but in a manner to cause it to turn in the reverse direction; thereby causing the material-transferring drum to be rotated.

The line or wire 69 contains a normally-open switch 58 which is held closed by the bucket 37 as long as the latter is at the bottom of the shaft. Therefore, while this switch does not prevent the operation of the motor for turning the cage, it prevents the motor from turning the drum except when the bucket is in position to receive material discharged by the drum.

It is desired that the motor stop whenever the cage or the drum, as the case may be, has been turned through a complete revolution. I accomplish this by providing means to keep the motor circuit closed for the necessary number of revolutions of the motor, after the main switch has been closed momentarily and then opened again. To this end I have provided automatic switches which, in the arrangement shown, include the rings of conducting material 62 and 67. Located below each of these rings is a rocking device including a contact finger 70; these rocking devices being biased in some suitable manner, as, for example, by providing them with counter-weights 71, so that normally they are out of engagement with their respective rings. Each of the rocker devices is also provided with a projecting arm 72 adapted to underlie and engage with the periphery of a ring beside and concentric with the corresponding ring of conducting material. These additional rings are indicated at 74 and 75. In the periphery of each of the rings 74 and 75 is a notch 76. The parts are so proportioned that when the free ends of the arm 72 register with the notches 76, the rocker devices move angularly in the direction to carry their contact fingers 70 away from the corresponding rings 62 and 67. However, upon turning the rings far enough to carry the notches clear of the ends of the arms 72, the arms must ride on the unmutilated portions of the peripheries of the rings 74 and 75, thereby pressing their contact fingers 70 against the rings 62 and 67, respectively. It will be seen that one of the contact fingers 70 is connected to the terminal 59 by a wire 71, while the other is also connected to this same terminal by a wire 73. Therefore, when either of the contact fingers 70 is engaged with its ring of conducting material, a motor circuit is established independently of the main switch. The parts are so proportioned in the actual machine or apparatus that the automatic switch of which the ring 62 forms a part, is open whenever the cage is in its normal position of rest, as indicated in Fig. 6, whereas the other automatic switch, including the ring 67, is open whenever the drum is in its material-receiving position, as indicated in Fig. 6. With this arrangement, upon swinging the handle of the main switch toward the right in Fig. 5, the circuit of the motor is momentarily closed through the main switch. As soon as the cage has rotated far enough to cause the arm 72 of the automatic switch to ride out of the notch 76 and upon the unmutilated periphery of the ring 74, a new circuit for the motor is established, and

the operator may then open the main switch. The motor continues to run until the cage has made a complete revolution, so as to permit the arm 72 of the corresponding automatic switch again to drop into the notch 76 and thereby cause this switch to open the motor circuit.

After the cage has made a complete revolution and the now-empty car has been restored to an upright position, the operator simply swings the switch handle toward the left, as viewed in Fig. 5, and, after the motor has again started, but in the reverse direction, again opens the switch. In the meantime, the second of the automatic switches has established a motor circuit independent of the main switch, so that the motor continues to run until the drum has been turned through a complete revolution; the motor then stopping automatically.

The mechanical construction of the automatic switch apparatuses is best shown in Figs. 7 and 10. It will be seen that the metal ring 62 forms a rim for a ring 79 of insulating material and of considerable radial width. The rings 74 and 79 are secured to the large gear wheel 41 by means of bolts 80. Likewise, the ring 67 surrounds and forms a rim on a disk 81 of insulating material which, in turn, is provided with a hub 82 fixed upon the trunnion or shaft section 38 of the drum unit. The ring 75 is shown as taking the form of a second disk of insulating material which is secured to the disk 81 by bolts 84. The rocker members of the automatic switches are mounted in the bottom of the pit 5 on suitable pedestals 85, each of the counter-weights being pivotally supported upon its pedestal by a pivot pin 86. It will be seen that the elements 70 and 72 are offset with respect to each other in the direction of the length of the pivotal axis, so that each underlies the ring or disk with which it operates.

The contact fingers 60, 64, 66 and 68 are mounted, in any suitable manner, in the pit in operative relation to the rings 62 and 67, as best shown in Figs. 8 and 9.

Any suitable couplings may be provided between cars, as long as they afford the freedom of relative movements required for cars operated in trains around curves and on grades, provided that each car is adapted to revolve about a longitudinal axis which registers with the axis of the cage when the car is positioned in the cage. In Figs. 12 to 14 I have illustrated a simple type of coupling which is satisfactory for my purpose. This coupling comprises a bar 87 of the proper length, shaped at each end into the form of a ball 88, together with socket members 89, one of which is adapted to be attached to each end of the under-frame or chassis of each car. Each socket member comprises simply a casting more or less U-shaped in cross section and having in the front end a slot 90 of approximately the same width as the diameter of the bar 87 extending down from the top thereof. The space within the casting, inwardly from the opening in the front, is made wide enough to permit the ball at one end of the bar to enter the same while the body portion of the bar passes down through the slot; and the surface immediately behind the wall in which the slot occurs is preferably shaped, as indicated at 91, to the same spherical curvature as that of the ball, so as to provide the ball with a good bearing seat and produce a satisfactory ball and socket joint between the car and the bar. The edges bounding the slot

at the top and at the bottom are flared in the outward direction so as to provide ample room for the bar to swing, not only up and down, but also sidewise, while the ball simply turns in its seat or socket.

Suitable means must be provided to hold each end of the bar in the sockets of two cars which are being connected by the bar. In the arrangement shown, the side walls of the socket are extended upwardly far enough at the front or outer end to permit them to be provided with registering transverse bores just above the bar when the latter is in place. The bar can then be held from being lifted out of its seat or socket by inserting a suitable pin or dog in the bores. In the arrangement shown, one side of the socket member is thickened in the outward direction to provide an elongated cylindrical casing 92 registering with the bore 94 in that side of the casting. The outer or free end of the casing 92 contains a central opening 95 smaller in diameter than the main bore. A rod 96 extends through the opening 94 and through the interior of the casing 92. On the inner end of the rod is an enlarged section 97 which is a sliding fit in the bores 94 and which is longer than the width of the slot 90. Within the casing, surrounding the rod, and bearing at one end against the outer end wall of the casing and at the other end against the shoulder formed by the enlarged part 97, is a compression spring 98 which acts constantly in a direction to force the part or plunger 97 into its locking position illustrated in Fig. 13. When it is desired to uncouple, the rod is simply pulled until the free end of the plunger or locking dog has been drawn entirely across and is clear of the slot 90, whereupon the coupling bar may be swung up so as to lift the ball out of the socket. The rod 96 may be of any desired length, and its outer, free end may be provided with a handle or handhold 99 to be grasped by the operator. If it be desired to limit the inward movement of the rod, so as to stop it when the plunger portion or locking element thereof has reached the desired position, a shoulder that may take any form as, for example, that of a pin 100, may be located on the rod for engagement with the end of the casing 92 when the plunger or locking element reaches its locking position.

It will thus be seen that I have produced a simple and novel apparatus or system for rapidly overturning each loaded car of a train when it reaches an unloading station, to empty it, without requiring it to be uncoupled from the other cars in the train; and that this may be done in any situation, whether underground or above ground. It will also be seen that I have made it possible, through the mere manipulation of a master switch, to empty a car in a tunnel or the like; deliver its contents to a point outside of the tunnel; and automatically restore the car to service conditions; all without permitting any appreciable amount of compressed air to escape from the tunnel during the process. It will further be seen that I have made it impossible to discharge material into the shaft for the hoisting apparatus unless the bucket or other receiving member of a conveying apparatus be in proper position to receive the material; although cars may be emptied into the air lock unit regardless of the condition in which the hoisting apparatus happens to be. It will additionally be seen that, aside from these broader aspects of the present invention, I have created a number of novel, useful details such as the car coupler, the structure

of the cage, the sealing means in the air-lock and material transfer unit.

It should be noted that although I have referred to the driving means for the apparatus simply as a motor, this designation is intended to include such speed reduction gearing as may be needed to translate the high speed of a motor into the low speeds at which the cage and drum must run; such gearing being either within the motor casing or in a separate casing. Also, since that part of the rotating element of the combined air-lock and material transferring unit that receives the dumped load is simply a pot or bucket having trunnions, the word drum is used as designating either this member, alone, or in combination with the cylindrical member that provides an effective air seal.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. An unloading apparatus comprising a movable combined air-lock and material transferring unit, a holder mounted above said unit for rotation about a horizontal axis and adapted to receive a car to be unloaded and dump its contents into said unit through a rotation of the holder, a motor, means to cause the motor to turn said holder, means to cause the motor to operate, said air-lock and material-transferring unit, a manually operable element having two working positions, and controlling devices to cause the first of the aforesaid means to become active when said element is placed in one working position and the other means to become active when said element is placed in the other working position.

2. An unloading apparatus comprising a movable combined air-lock and material transferring unit, a holder mounted above said unit for rotation about a horizontal axis and adapted to receive a car to be unloaded and dump its contents into said unit through a rotation of the holder, a motor, means to cause the motor to turn said holder through a complete revolution or to operate said air-lock and material transferring unit through a complete cycle from a receiving position through a discharge position and back to the receiving position, and a manually operable controller to determine which of said means shall operate at any given time.

3. An unloading apparatus comprising a movable combined air lock and material-transferring unit, a movable holder above said unit to receive a car to be emptied and turn it over to empty its contents into said air-lock and material-transferring unit, a motor, drive mechanism between said motor and said holder to operate the latter when the motor runs in one direction, other drive means to operate said unit when the motor is reversed, and means to cause the motor to run alternately in opposite directions.

4. An unloading apparatus comprising a movable combined air-lock and material transferring unit, a movable holder above said unit to receive a car to be emptied and turn it over to empty its contents into said air-lock and material transferring unit, a motor, drive mechanism between said motor and said holder to operate the latter when the motor runs in one direction, other drive means to operate said unit when the motor is reversed, a source of electric current, a manu-

ally-operable switch to connect said motor to said source for either forward or reverse operation, and means associated with the said unit and with said holder to keep the motor running independently of said switch, after having been started by the latter, until the holder or the said unit, as the case may be, has completed a cycle of operations.

5. An apparatus for disposing material, comprising a material-transferring unit containing a horizontal rotatable drum adapted to receive material in one angular position and to discharge the material in another angular position, a holder for a car to be dumped positioned above the said unit and rotatable about a horizontal axis, a gear wheel to turn said holder, a ratchet wheel fixed to said gear wheel, a second, oppositely-facing ratchet wheel fixed to the drum; a rotary driving member, and oppositely-disposed pawls carried by said member each of which operates on one of said ratchets, whereby the turning of the driving member in one direction causes it to drive said holder and the turning of the driving member in the opposite direction causes it to drive said material-transferring unit.

6. An apparatus for disposing material, comprising a material transferring unit containing a horizontal rotatable drum adapted to receive material in one angular position and to discharge the material in another angular position, a holder for a car to be dumped positioned above the said unit and rotatable about a horizontal axis, a gear wheel to turn said holder, a ratchet wheel fixed to said gear wheel, a second, oppositely facing ratchet wheel fixed to the drum; a motor-driven shaft, and oppositely-disposed pawls carried by said shaft each of which operates on one of said ratchets, whereby the turning of the shaft in one direction causes it to drive said holder and the turning of the shaft in the opposite direction causes it to drive said material-transferring unit, a master switch for the motor, and automatic switches operated in unison with said holder and said unit to cause the motor to run for predetermined periods after having been started by the momentary closing of the switch.

7. A combined air-lock and material transferring apparatus comprising a horizontal cylindrical casing closed at the ends and having top and bottom openings of considerable angular width, a horizontal cylindrical drum positioned and rotatable in said casing and having an opening adapted to register with either of the aforesaid openings, said drum being somewhat smaller in diameter than the internal diameter of the casing and having its ends closed by the end walls of the casing, external flanges on the ends of the drum bridging the gap between the latter and the surrounding cylindrical wall of the casing, a packing ring surrounding the drum beside each flange, and means to clamp each ring to the adjacent flange and expand it radially against the cylindrical wall of the casing.

8. A combined air lock and material transferring apparatus comprising a horizontal cylindrical casing closed at the ends and having top and bottom openings of considerable angular width, a horizontal cylindrical drum positioned and rotatable in said casing and having an opening adapted to register with either of the aforesaid openings, said drum being somewhat smaller in diameter than the internal diameter of the casing and having its ends closed by the end walls of the casing, external flanges on the ends of the drum bridging the gap between the latter and

the surrounding cylindrical wall of the casing, a packing ring surrounding the drum beside each flange, means to clamp each ring to the adjacent flange and expand it radially against the cylindrical wall of the casing, longitudinal ribs distributed about and fixed to the periphery of the drum, a loose clamping strip beside each rib, a packing strip between each rib and the corresponding clamping strip, and means to draw each rib and the co-operating clamping strip together to hold the intervening packing strip and expand it radially into engagement with the cylindrical wall of the casing.

9. A combined air-lock and material transferring unit comprising a horizontal stationary cylindrical casing closed at the ends by end walls and having in the top and bottom long openings of considerable angular width, a rotatable cylindrical open-ended member fitted into and rotatable in said casing and having an opening adapted to register with either of the openings in the

casing, an open-top receptacle fixed within said rotatable member with its mouth coincident with the opening in that member, and trunnions extending from said receptacle through said end walls.

10. A combined air-lock and material transferring unit comprising a horizontal stationary cylindrical casing closed at the ends by end walls and having in the top and bottom long openings of considerable angular width, a rotatable cylindrical open-ended member fitted into and rotatable in said casing and having an opening adapted to register with either of the openings in the casing, an open-top receptacle fixed within said rotatable member with its mouth coincident with the opening in that member, trunnions extending from said receptacle through said end walls, and a counterweight on one of said trunnions to balance the rotatable structure.

SETH M. GOODER.
